NONREFILLABLE ATTACHMENT

Jacob W. Schieber, Scranton, Pa.

Application July 23, 1935, Serial No. 32,816

3 Claims. (Cl. 215—30)

This invention relates to a non-refillable attachment for bottles, jugs and containers, and is designed primarily for use in connection with bottles containing high grade liquors, wines, perfume, fumes, etc., but it is to be understood that the attachment, in accordance with this invention, may be employed in connection with any type of container for which it is found applicable.

The object of the invention is to provide, in 10 a manner as hereinafter set forth, an attachment of the class referred to which, when in anchored position with respect to the bottle, will prevent the surreptitious refilling of the bottle after the original contents of the latter have 15 been discharged.

A further object of the invention is to provide, in a manner as hereinafter set forth, an attachment, for the purpose referred to, which will permit a steady discharge, with no surging action, 20 of the contents of a bottle when the latter is tilted from the vertical to beyond the horizontal, and further will prevent discharge from the bottle when the latter is disposed in a vertical inverted position.

25 Further objects of the invention are to provide, in a manner as hereinafter set forth, a non-refillable attachment for bottles, jugs and containers which is simple in its construction and arrangement, readily installed with respect to the 30 neck of a bottle, jug or container, strong, durable, compact, thoroughly efficient in the use intended thereby, and comparatively inexpensive.

With the foregoing and other objects in view, the invention consists of the novel construction, 35 combination and arrangement of parts as will be hereinafter more specifically described and as are illustrated in the accompanying drawing wherein is shown an embodiment of the invention, but it is to be understood that changes, 40 variations and modifications may be resorted to which fall within the scope of the invention as claimed.

In the drawing:

45 Figure 1 is an elevation of one of the two like sections of the attachment looking towards the inner face of such section,

Figure 2 is a fragmentary view in vertical section illustrating the attachment anchored to the neck of a bottle,

50 Figure 3 is a section on line 3—3, Figure 2,

Figure 4 is a view looking towards the inner face of one of the two like sections of the attachment and with such section angularly disposed in a position to provide for the discharge 55 of the contents of the bottle,

Figure 5 is a fragmentary view in side elevation of the bottle with which the attachment is to be employed,

60 Figure 6 is a top plan view of the neck of the bottle,

Figure 7 is a sectional plan of the upper valve, Figure 8 is a sectional plan of the lower valve, Figure 9 is an inverted plan view of the attachment,

Figure 10 is a section on line 10—10, Figure 1,

Figure 11 is a section on line 11—11, Figure 1,

Figure 12 is a top plan view of the attachment, and

Figure 13 is a vertical sectional view of a modified form.

Referring to the drawing, 1 indicates the body of the bottle and 2 the neck of the latter. The outer face of the neck 2 is formed with a pair of diametrically opposed oppositely extending bayonet-shaped grooves 3 opening at the top edge 4 of the neck. Positioned on edge 4 of neck 2 is a washer 5.

The attachment includes a pair of oppositely disposed sections 6, 7 of like form, a plurality of coupling members 8 for anchoring the sections 6, 7 together, an upper valve 9 and a lower valve 10. The sections 6, 7 are formed of like material and a material possessing a characteristic which will permit of parts of the coupling members 8 embedding therein whereby, when the coupling members 8 are in position, the sections 6, 7 can- 25 not be separated relatively to each other.

The description of one of the sections of the attachment will apply to the other and each sec- 30 tion comprises a one-piece body 11 of the desired length and width and formed with a flat inner face 12. The body 11 includes an upper end portion 13, an upper intermediate portion 14

35 which projects laterally in both directions from the portion 13, a lower intermediate portion 15 of less width than the upper intermediate portion 14, and an inner end portion 16 which is outset with respect to the portion 15. The portion 16 merges outwardly. The portion 16 merges 40 into the outer marginal part of the inner end of the portion 15. The inner face of portion 13 is formed with a semi-circular groove 17. The inner face of the portion 14 is formed with a pair of oppositely disposed grooves 18, 19 which open 45 into the inner end of the groove 17. The groove 18, as well as the groove 19, is formed of an inwardly extending upwardly inclined upper branch 20, an upstanding inwardly inclined intermediate branch 21 which merges at its upper end into the lower end of the branch 20, and an inwardly 50 extending lower branch 22 which merges at its outer end into the branch 21 above the lower end of the latter. The grooves 18 and 19 have their lower ends spaced from each other and form the inner face of body 11 with an abutment portion 23 having oppositely downwardly inclined top edges 24, 25. The inner face of the portion 15 is 55 formed with a pair of oppositely disposed spaced like grooves 26, 27 which open at their upper ends 60 into the branches 22 adjacent the inner ends of

said branches. The grooves 26, 27 incline from their upper ends in an outward direction towards their lower ends. The lower ends of the grooves 26, 27 are arranged above the lower end of the portion 15. The latter is formed with a pair of opposed spaced oppositely disposed semi-circular grooves 28, 29 which open into the grooves 26, 27, respectively, above the lower ends thereof. The grooves 28, 29 extend inwardly substantially 5 at right angles to the grooves 26, 27, respectively. The inner face of portion 15, lengthwise thereof, is formed with an elongated cavity 30 substantially of frusto-ovoidal contour, of semi-circular cross-section. The cavity 30 gradually increases 10 in width in opposite directions from its ends. The cavity 30 is intersected centrally thereof by the lengthwise median of the body 11. The depth of the cavity 30 is greater than the depth of the grooves 28, 29 and these latter open into opposite 15 sides of the cavity 30 intermediate its ends. The inner face of portion 15 at the lower end of the latter is formed centrally with a semi-circular groove 31 which opens into the bottom of the cavity 30. The portion 16 is of semi-circular 20 contour and has formed on its inner face, centrally thereof, a lug 32. The groove 31 is disposed adjacent to the inner face of portion 16. The inner face of the portion 14 is formed with a socket 33 centrally thereof. The inner face of 25 the portion 15, between the side walls of cavity 30 and the side edges of the body 11, is formed with a pair of spaced parallel sockets 34, 35 which are arranged in spaced relation with respect to the lower ends of the grooves 26, 27.

30 When the sections 6, 7 are anchored together, the non-grooved parts of the inner faces of the portions 13, 14 and 15 of section 6 abut the non-grooved parts of the inner faces of the portions 13, 14, 15 of the section 7 and the side edges of the portion 16 of section 6 abut the side edges of the portion 16 of section 7. When the sections 6, 7 are arranged in abutting relation, the sockets of the section 6 register with the sockets of the section 7.

40 Three coupling elements or members 8 are employed and they are of like form. Each coupling element 8 consists of a short length of cylindrical stock 36 formed with barbs 37. The coupling elements 8 are arranged in the registering sockets 50 and the barbs of said elements embed themselves in the material forming the sections 6, 7 whereby said elements 8 function to anchor the sections 6, 7 in abutting relation. When the sections 6, 7 are in abutting relation, the grooves 17 of said sections 55 coat to provide a combined fluid outlet and air intake port 38 (Figure 12) and which also constitutes a pocket or socket for the reception of a cork or closure 39 (Figure 2). The base of the socket which receives the cork 39 is formed 60 by the inclined edges 24, 25 of the abutment portion 23.

When the sections 6, 7 are anchored together, the grooves 18, 26 and 28 of the section 6 coat with the grooves 18, 26 and 28 of the section 7 65 to provide a tortuous tubular passage 40 (Figure 4). The passage 40 is formed with an inward extending lateral tubular branch arranged outwardly of and in proximity to its inner end. The function of the branch will be presently referred 70 to. The grooves 19, 27 and 29 of the section 6 coat with the grooves 19, 27 and 29 of the section 7 to provide a tortuous tubular passage 41 (Figure 4). The passage 41 has an inwardly extending lateral tubular branch arranged outwardly of and in proximity to its inner end,

The function of the branch of the passage 41 will be presently referred to. The passages 40, 41 are oppositely disposed and closed at their inner ends. The passages 40, 41 are open at their outer ends. The branches of the passages 40, 41 are open at each end thereof. The outer ends of the passages 40, 41 open into the inner end of the port 38 at opposite sides of the latter. When the cork 39 is mounted in position, it closes the outer ends of the passages 40, 41.

The cavity 30 of the section 6 coacts with the cavity 30 of the section 7 to provide a valve chamber 42 (Figure 2) which is closed at its outer end. The lateral branches of the passages 40, 41 are provided between grooves 28, 29 of the sections 6, 7 and form outlets for the valve chamber 42. The lateral branches of the passages 40, 41 communicate with said chamber at opposite sides of the latter and also intermediate the ends of the chamber. The groove 31 of section 6 coacts with the groove 31 of section 7 to provide a fluid intake 43 (Figure 2) for and at the inner end of the chamber 42. The portion 16 of the section 6 coacts with the portion 16 of section 7 to form a coupling band 43a (Figures 9 and 12). 20

The passage 40 may be employed for solely discharging the liquid or for simultaneously discharging liquid and intaking of air. The passage 41 may be employed solely for discharging liquid or for simultaneously discharging liquid 30 and intaking of air. The passages 40, 41 intermediate their ends are provided with oppositely extending closed outer end branches as indicated at 46a and 48 (Figure 4). The closed inner ends of the passages 40, 41 are indicated at 47a 35 (Figure 4). The lateral branches of the passages prevent the insertion of a wire or other element into the passages to an extent to hold the valve 10 from off its seat to permit of surreptitiously refilling the bottle. 40

After the sections 6, 7 have been anchored together, they are connected to the neck 2 by the coaction of the lugs 32 with the grooves 3, but prior to the connecting of the attachment to the bottle 1 the periphery of the neck is provided with a cementitious material 44 arranged in the groove 3 and inwardly adjacent the latter. The cementitious material will be of a characteristic to securely hold the attachment to the bottle and to prevent the separation of the attachment from the bottle unless the neck 2 or portion 16 of the sections 6, 7 break in two when an attempt is made to separate the attachment from the bottle. 45

The lower portion of the wall of the valve chamber 42, and which is indicated at 45, provides 55 a valve seat for the valve 10, the latter being of globular form. The valve 10 is hollow. The valve 9 is of globular form and weighted as at 46. The valve 9 bears against the valve 10 and tends to maintain the latter on its seat when the attachment is vertically disposed. When the attachment is arranged at an angle to the horizontal, the valves 9, 10 move to the dotted line position shown in Figure 2 and their movement is arrested by the end wall 47 (Figure 2) of the chamber 42. 60 65

If the bottle is tilted with respect to the horizontal to the right, the passage 40 provides for solely discharging the fluid and the passage 41 not only provides for the discharge of fluid but also for the intake of air. If the bottle is tilted with 70 respect to the horizontal to the left, then the passage 41 provides solely for the discharge of fluid or liquid and the passage 40 not only provides for the discharge of the fluid or liquid but also for the intaking of air. 75

The parts of the attachment are so arranged to provide for discharge of the contents of the bottle after the attachment is disposed at an angle with respect to the horizontal and as the attachment, when extending downwardly, is moved towards the vertical, the flow decreases and completely stops when the attachment assumes an inverted vertical position. It is thought that the preventing of discharge from the bottle, when the attachment is in an inverted position and vertically disposed, is due to an air-trap effect within the attachment.

The attachment is for employment in connection with any form of container having a neck or an annular extended intake or filling member. The term container is also meant to imply a bottle or a jug. The term neck is also meant to imply an annular extended intake or filling member.

With reference to Figure 13, the attachment includes a one-piece body 49 of glass which corresponds in all particulars to the resultant structure provided by the sections 6, 7, when these latter are anchored together, with this exception, that the inlet 50 to valve chamber 51 is provided by an annular acid resisting disc 52 positioned against the countersunk inner end or edge 53 of the portion 54 of body 49. The portion 54 corresponds to the combined portions 15 of the sections 6, 7. The sockets 34 and elements 8 are not included. The disc 52 is applied to the edge 53 after the valves 55, 56 are inserted in the valve chamber 51. The disc 52 seats on washer 5. Otherwise than that as stated, the form of attachment shown in Figure 13 will be the same as that shown in Figure 2.

What I claim is:

1. A non-refillable attachment for containers of the neck type comprising a structure adapted to be secured to and extend from the container neck and provided intermediate its ends with a valve chamber closed at its outer end and having an open inner end for communication with the neck of the container, the open inner end of said valve chamber constituting an intake for the latter, a valve seat within said chamber at the inner end of the latter, a pair of spaced oppositely disposed tortuous independent passages lengthwise thereof and between which is arranged said chamber, each of said passages including an inwardly inclined closed inner end inner stretch, a horizontally disposed closed inner end intermediate stretch and an inwardly inclined closed inner end outer stretch, said inner stretch opening into said horizontal stretch intermediate the ends of the latter and said horizontal stretch opening into said outer stretch, each of said passages adjacent its inner end being formed with a lateral tubular branch opening into one side of said chamber intermediate the ends of and constituting an outlet for the latter, said structure including a combined fluid outlet and air intake at its outer end opening into the atmosphere and common to and opening into the outer ends of said outer stretches, valvular means arranged within said chamber and coacting with said seat to close said inlet, and said combined fluid outlet and air intake providing a socket for normally receiving a stopper to close the outer ends of said passages.

2. A non-refillable attachment for containers of the neck type comprising a structure formed of a pair of inner sidewise abutting oppositely disposed like sections and means within said sections for anchoring them together in abutting relation, said

sections having their inner end portions coacting and being so formed for connecting said structure in encompassing relation with respect to the container neck, said sections being formed with coacting oppositely disposed means to provide within 5 said structure a valve chamber closed at its outer end and open at its inner end, the open inner end of said valve chamber constituting an intake for establishing communication between said chamber and the container neck, said sections being 10 formed intermediate their ends with coacting means for seating upon the container neck and with coacting means to provide a valve seat at the inner end of said chamber, said sections having coacting means on their inner sides to form said 15 structure with oppositely disposed tortuous tubular passages lengthwise thereof outwardly adjacent said chamber and communicating adjacent their inner ends with said chamber at opposite sides and intermediate the ends of the latter for 20 fluid discharge and air intake, said sections having coacting means at their outer ends to provide said structure with a combined fluid outlet and air intake common to the outer ends of said 25 passages, valvular means arranged within said chamber and coacting with said seat to close said inlet, and said combined fluid outlet and air intake being spaced from and free of direct communication with said chamber and providing a 30 socket for normally receiving a stopper to close the outer ends of said passages.

3. A non-refillable attachment for containers of the neck type comprising a structure formed of a pair of inner sidewise abutting oppositely disposed like sections and means anchored within 35 said sections for securing said sections in abutting relation, said sections having their inner end portions coacting and being so formed to provide means for connecting said structure in encompassing relation with respect to the container 40 neck, said sections being formed with coacting means on their inner sides to provide said structure intermediate its ends and centrally thereof with a valve chamber closed at its outer end and open at its inner end for communicating with the 45 container neck, the open inner end of said valve chamber constituting an intake, said sections being provided with coacting means to provide a valve seat at the inner end of said chamber, said sections having their inner sides provided with 50 oppositely disposed coacting means to form said structure with spaced tortuous independent tubular passages lengthwise thereof, adjacent opposite sides of and extending outwardly with respect to the closed outer end of said chamber, said 55 passages for fluid discharge and air intake, said passages being closed at their inner ends and provided with tubular branches forwardly adjacent their inner ends opening into opposite sides of said chamber intermediate the ends of the 60 latter and providing outlets for the chamber, said passages being open at their outer ends, said sections, at their outer ends, being provided with coacting oppositely disposed means to provide said structure with a combined fluid outlet and air intake opening into the atmosphere and into the 65 outer ends of said passages, valvular means arranged in said chamber and coacting with said seat for closing the inner end of said chamber, and said combined fluid outlet and air intake providing a socket for normally receiving a stopper to close the outer ends of said 70 passages.
